UNITED STATES PATENT OFFICE.

GEORGE HOFFMAN, OF MOUNT VERNON, NEW YORK.

LOUNGE.

SPECIFICATION forming part of Letters Patent No. 373,977, dated November 29, 1887,

Application filed December 21, 1886. Serial No. 232,214. (No model.)

To all whom it may concern:

Be it known that I, GEORGE HOFFMAN, of Mount Vernon, in the county of Westchester and State of New York, have invented a new 5 and Improved Lounge, of which the following is a full, clear, and exact description.

The object of this invention is to provide a lounge having a reversible back, so that when desired the lounge may be easily and quickly 10 changed from a right to a left hand lounge, or vice versa.

The invention consists in the construction and combination of the various parts, as will be hereinafter more fully described and 15 claimed.

Reference is to be had to the accompanying drawings, forming a part of this specification, in which similar letters of reference indicate corresponding parts in all the figures.

20 Figure 1 is a perspective view of my improved lounge. Fig. 2 is a plan view of the back of the lounge. Fig. 3 is an end view showing a modified form of levers, parts being broken away. Fig. 4 is a sectional view 25 on the line $x-x$ of Fig. 2.

A designates in the drawings the frame of the lounge, B the legs thereof, and C the armrest. (Shown in dotted lines.) This rest C is made separate from the frame A, so that it 30 can be removed to allow of the back being swung over from side to side. The frame A is to be provided with the usual springs and upholstery.

Passing through the longitudinal center of 35 the frame A is a shaft, D, which is journaled in the ends of the frames and supported in grooves in the cross-slats a . This shaft has the spur-wheels b mounted thereon.

The slides E, which support the back, pass 40 through the frame of the lounge from side to side and have upwardly-projecting lugs E' , which are adapted to fit into recesses c . These recesses c are on both sides of the frame A, so that when the lugs E' on the slide E project from one side of the lounge those on the opposite side fit snugly into the recesses c , thus preserving the harmony of the fancy-work which may be on the frame A. The slides E are bent up at their centers, as at d ,

and have teeth e formed on the under surface 50 at said bend, which mesh with the spur-wheels b . Thus when the shaft D is rotated, by means hereinafter described, the spur-wheels b rotate, and as they mesh in the teeth e on the slides E the said slides are moved 55 from side to side and the lugs E' forced out of the recesses c to support the back F when swung over. The ends of the shaft D project slightly from the end of the frame A and are squared to fit into the square apertures in 60 the levers G, which are attached to the back F of the lounge. Thus when the back is swung over from right to left, or vice versa, the levers G cause the shaft D to rotate for the purpose of moving the slides from side to side, as 65 above described.

The levers G in Fig. 1 have eyebolts H, the eyes h of which work up and down on rods i in the ends of the back F. By this arrangement the back F may be swung over without 70 impediment from the levers G, as the bolt H will slide up and down the rod i when the back is being swung over.

In Fig. 3 I have shown the levers G having elongated slots j , in which the pivots k on the 75 back F of the lounge work, substantially for the same purpose.

The back F is made, with a view to ornamentation, with one part or section, f' , lower than the other section, f . In order to have 80 the back F correspond in this respect when thrown from one side to the other, the section f' is provided with the tenon or head g , adapted to work in a mortise, g' , in the section f . Thus, as in Fig. 2, the section f' can be moved 85 from the position shown in full lines to that shown by dotted lines. This change in position of the section f' relatively to section f becomes necessary when the back is changed from right to left. m is an ornamental block 90 adapted to be inserted in the space between the tops of the sections f and f' .

Having thus fully described my invention, what I claim as new, and desire to secure by Letters Patent, is—

1. The combination, with the frame and the hinged back, of the levers carrying supports which slide into and out of the frame, provid-

ing for receiving the normally lower edge of the back between the frame and supports, substantially as and for the purpose set forth.

2. The combination, with the frame A, of the back F, levers G, shaft D, carrying spur wheels b, sliding supports E, having lugs E', and teeth e, substantially as shown and described.

3. In a lounge, the swinging back F, made substantially of the sections f and f', the section f' adapted to slide on and arranged lower than the section f, as described.

GEORGE HOFFMAN.
